CAN END FEEDING MEANS

Ferdinand Kastel, Baltimore, Md., assignor to
 Continental Can Company, Inc., New York,
 N. Y., a corporation of New York

Application August 20, 1945, Serial No. 611,470

13 Claims. (Cl. 113—114)

1 The invention relates generally to can end feeding means and seeks to provide novel means for individually and positively feeding can ends of the hat shaped type from the stack in which they are retained as a multiple supply to a work station or stations at which they are attached to can bodies, or otherwise worked upon, as by having sealing compound applied thereon and being edge curled preparatory to subsequent attachment to can bodies.

Can ends of the hat shaped type have raised central portions providing heels snugly insertible in can body ends and which are surrounded by outwardly extending flat flanges terminating in raw edge portions, and when can ends of this type are stacked, considerable difficulty is experienced in feeding the ends one by one from the bottom of the stack because of the tendency of the raised central portions of the can ends to partially nest. It is therefore an object of the present invention to provide novel means for stacking can ends of the type stated and for first effecting a definite separation of the lowermost can end in the stack from the overlying can ends, and then feeding the separated end from beneath said overlying can ends.

An object of the invention is to provide in stacking and feeding means of the character stated a novel depressor finger which is moved in a four-motion path to first engage between two can ends at least as high as the second and third can ends at the bottom of the stack, then move downwardly to press the outwardly projecting end flanges together at the engaged sides of the ends and cause the flanges at the opposite sides of said ends to move apart and effect a separation of the adjacent portion of the lowermost can end from the adjacent portion of the overlying or second can end, then move outwardly from between said can end flanges, and then upwardly to complete the four-motion movement, means also being provided for moving between the separated first and second can end portions to effect a complete separation of the first can end from the rest of the stack, and also means for engaging said first can end and moving it from beneath the stack.

Another object of the invention is to provide in can end stacking and feeding means of the character stated a support element projecting into the space in which the can ends are stacked opposite the depressor finger and at an elevation for supporting the weight of the major part of the can end stack at that side so that this supported weight will not resist upward movement of separation of the can end flanges incidental to

2 the depressing action of said finger, said support element also being effective to prevent upward agitation of the can ends at the bottom of the stack incidental to the successive separation and feeding of can ends being transmitted to can ends in the upper part of the stack in a manner tending to displace can ends from the top of the stack.

Another object of the invention is to provide in can end stacking and feeding means of the character stated, magnet means effective to securely hold the first or lowermost can end in position while the overlying can ends are being separated therefrom preparatory to the feeding away of said lowermost can end.

Another object of the invention is to provide in can end stacking and feeding means of the character stated a stack holder having a movable wall portion, and means for displacing said wall portion to provide a clearance through which the separated lowermost can end can be fed away.

Another object of the invention is to provide in can end stacking and feeding means a depressor finger of the character stated which projects from the lower end of an uprightly disposed arm having a horizontally projected portion at its upper end, pivot pin means traversing the arm at the juncture thereof with the horizontally projected portion and slidably and frictionally engaging at its ends in a guideway, means limiting inward and outward movement of the free end of the arm, and means for imparting upward and downward movement to the horizontally projected portion to cause the depressor finger to partake of a four-motion movement resulting from a pivoting of the arm about the pin means and upward and downward sliding of said pin means.

With the above and other objects in view that will hereinafter appear, the nature of the invention will be more clearly understood by reference to the following detailed description, the appended claims, and the several views illustrated in the accompanying drawings.

In the drawings:

Figure 1 is a side elevation somewhat diagrammatically illustrating a machine embodying the invention.

Figure 2 is an end elevation of the machine structure shown in Figure 1.

Figure 3 is an enlarged vertical cross sectional view taken on the line 3—3 on Figure 1.

Figure 4 is an enlarged central longitudinal sectional view taken on the line 4—4 on Figure 3.

Figure 5 is a plan view illustrating the parts shown in Figures 3 and 4.

Figure 6 is an enlarged fragmentary vertical cross section taken in the plane in which the stack housing member lifting cam bar reciprocates, the bar being shown in the housing member lifting position.

Figure 7 is a detail horizontal section taken on the line 7—7 on Figure 4.

Figure 8 is a detail horizontal section taken on the line 8—8 on Figure 4.

Figure 9 is a detail horizontal section taken through the position of the pivotal mounting of the depressor finger equipped arm.

Figures 10, 11, 12 and 13 are somewhat diagrammatic vertical longitudinal sectional views illustrating four successive positions in the four-motion movement of the can end depressing finger.

Figure 14 is a vertical cross section taken on the line 14—14 on Figure 13.

Figure 15 is a fragmentary vertical longitudinal section illustrating one acceptable mounting of the feed bar feed fingers.

Figure 16 is an enlarged fragmentary view partly in section illustrating the connection between the depressor finger actuator arm and the actuator rod.

In the example of embodiment of the invention herein disclosed, the improved can end stacking and feeding means is shown in a combined machine structure including the stacking and feeding means generally designated A, a work station generally designated B whereat the can ends have a sealing compound applied thereon, a work station C whereat the can ends are edge curled, and a restacking station D. The present invention has to do only with the can end stacking and feeding means A, and the other parts or stations are shown only to illustrate the cooperative relation and the various drives for the parts of said stacking and feeding means. The sealing compound applying means and the edge curling means are not shown, the stations whereat they are located alone being indicated by the characters B and C.

Referring to Figures 1 and 2, it will be apparent that in the machine referred to, there is included a base 5 from which rises standard portions 6 and 7 on the latter of which the work station C is supported, and said standards support a feed bed 8 wherein is provided a longitudinal groove 9 in which is reciprocably mounted a feed bar 10 equipped with the usual depressible feeder fingers 11. The feeder fingers may be constructed in any approved manner, and an example of a satisfactory structure is illustrated in Figure 15.

The feeder bar 10 has a bracket 12 secured thereto in the manner illustrated in Figure 1, and said bracket is adjustably connected as at 13 to the upper end of an actuator arm 14 which is pivotally mounted intermediately of its ends as at 15 on a bracket 16 which is secured to the frame standard 1. The actuator arm 14 extends below its pivotal mounting at 15 and is link connected as at 17 to a crank pin 18 projecting from a crank disk 19 secured on the main driver shaft 20. It will be apparent that as the crank disk 19 is rotated, the rotary motion of said disk will be transmitted in the form of reciprocatory movement to the feeder bar 10.

The driver shaft 20 is connected by a one to two bevel couple 21 with a cam shaft 22 which is horizontally disposed and rotatably mounted in frame bearings 23 and 24. It will be apparent

that the cam shaft 22 rotates once for each two rotations of the main driver shaft 20. It will be apparent by reference to Figures 1 and 2 that a cam 25 is fixed to the extended end of the shaft 22, and the said cam is provided with two diametrically oppositely disposed crests or lobes 26 separated by two concentric dwell portions, the effective portion of each crest starting at the end of one of the concentric portions, and ending at 28 at the commencement of the other of said concentric portions.

The periphery of the cam 25 cooperates with a roller 29 projecting from one end of a slide actuator lever 30 which is pivoted on the frame 15 intermediately of its ends as at 31 and is connected at its other end with a slide actuator rod 32. The rod 32 is normally retracted, or in other words constantly urged downwardly, by a retractile spring 33 which is anchored as at 34 on the frame base 5. At its upper end the rod 32 is slot and pin connected as at 35 to two bell crank slide actuating levers 36, each of which is pivoted, as at 37, and connected as at 38 at its upper end with an ear 39 depending from a slide 40. The two slides are slide-guided as at 41 in transverse extensions 42 provided on the bed 8. See Figures 1, 2, 3 and 5.

The cam shaft 22 drives a second cam shaft 43 through sprocket and chain connections 44, said second cam shaft being disposed at a higher level and in parallel relation to the shaft 22 and rotatable in bearings 45, one of which is supported on a bracket 46 secured to the frame standard 1, and the other of which is supported 35 on a bracket 47 secured beneath the bed extensions 42 and upon which the bell crank levers 36 are pivotally mounted.

It will be apparent by reference to Figures 1 and 2 that an actuator cam 48 is fixed on the cam shaft 43 beneath one of the bed extensions 42, and said cam is equipped with two diametrically oppositely disposed crests or lobes 49 which are connected by gradually sloping sides with two intermediate concentric portions 50. The purpose of the cam 48 will become apparent as the description progresses.

Referring now to Figures 1 through 5, it will be observed that two support bars 51 are secured as at 52 in parallel spaced relation on the bed 8 across the feeder bar groove 9. On each bar 51 an angle member 53 is secured as at 54. To the angle member 53 shown at the left in Figures 1 and 4 an upright U-shaped support and stop member 55 is secured as at 56. The member 55 is in turn secured as at 57 to the upright stack housing member 58 which is arcuately shaped at its inner face to conform to the ends of the can ends which are stacked between said housing member and a companion housing member. In 60 this particular disclosure, the stacking and feeding apparatus is adapted to stack and feed can ends which are elliptical or oval in shape, but it is to be understood that the apparatus is adapted for the stacking and feeding of can ends of various shapes, and that the opposing faces of the housing members will be shaped according to the shapes of the can ends which are being stacked and fed.

It will be apparent by reference to Figures 4 70 and 8 that the housing member 58 is U-shaped at its outer face to conform to the opposing face of the member 55 and cooperate therewith in providing a depressor finger receiving chamber having an outer stop wall 61 for cooperating with 75 the inner stop wall formed by the outer face of

the U-shaped portion of said housing member. The said opposing stop walls serve to limit inward and outward swinging movement of the depressor finger to be described in detail hereinafter.

Above the member 55, two angle pieces 62 are secured uprightly in parallel spaced relation as at 63 to the housing member 58, and these angle pieces cooperate with the housing member 58 in providing a depressor finger receiving chamber and stop walls 64 which are vertically aligned with the previously mentioned stop wall 61. It should be understood that the housing member 58, the member 55 and the pieces 62 may be formed integrally, if desired.

A block 65 is secured across the upper end of the pieces 62 as at 66, and said block is provided with a finger piece extension receiving opening 67. It will also be apparent by reference to Figures 3 and 4 of the drawings that an adjustable stop screw 68 is threaded through the block 65 in position for extending downwardly through the upper wall of the opening 67, and a similar adjustable stop screw 69 is threaded through the block 65 in position for extending upwardly into said opening. The purpose of the extension receiving opening 67 and the stop screws 68 and 69 will soon be described.

An opening 70 is provided through the outer wall 60 of the housing member 58 at the bottom, and a horizontally disposed depressor finger 71 is disposed to operate in and through said opening. The finger 71 projects inwardly from the lower end of a carrier arm 72 which is uprightly disposed in the chamber formed between the outer wall 60 of the housing member 58 and the previously mentioned stop walls 61 and 64. The arm 72 is provided with an outwardly extended horizontal portion 73 at its upper end which extends into and is vertically movable in the block opening 67, and said extension 73 has an actuator pin 74 projecting therefrom in the manner clearly illustrated in Figures 2 and 4 of the drawings.

By reference to Figures 1 to 5 and 9 of the drawings, it will be apparent that the arm 72 is equipped with a transverse bore 75 at the juncture thereof with the horizontal extension 73, and in said bore there are mounted two axially aligned pivot pin buttons 76 which are surrounded and pressed apart by a compression spring 77. The spring presses the outer ends of the buttons 76 in tight frictional contact with the side walls of the chamber in which the arm 72 is mounted and said buttons serve as a slidable pivot mounting for said arm. In other words, the arm may pivot about the common axis of the buttons 76, and may slide upwardly and downwardly in its mounting chamber, said buttons serving to frictionally retain the arm in the positions to which it is moved.

The pin 74 extending from the arm extension 73 engages in an elongated slot 78 provided intermediate of the ends of an actuator arm 79 which is pivoted at one end as at 80 on a bracket 81 secured as at 82 to one side of the housing member 58. At its free end the arm 79 is provided with an apertured horizontal portion 83, the aperture of which loosely surrounds an actuator stem 84 having an enlarged stop shoulder 85 engageable under said portion 83. The stem 84 including the abutment shoulder 85 is adjustably mounted as at 86 at the upper end of an actuator rod 87 and the arm portion 83 is yieldably held against the stop 85 by a compression spring 88 which surrounds the stem 84 above the arm portion 83 and beneath an abutment

means 89 adjustably mounted at the upper end of said stem. See Figures 2 and 16.

A compression spring 90 surrounds the rod 87 beneath the abutment formed by the member on which the stop shoulder 85 is formed and a guide 91 through which said rod extends in the manner clearly illustrated in Figure 2, and it will be apparent that the spring 90 will constantly urge the stop shoulder 85 against the under surface of the arm portion 83 and constantly tend to lift the arm and cause the depressor finger carrying bar extension 73 to engage the upper adjustable stop 68 in the manner illustrated in Figure 4. The lower end of the rod 87 which extends downwardly through the guide 91 is attached to a slide 92 having an elongated slot 93 straddling the cam shaft 43, said slide being disposed closely adjacent the cam 48 in the manner clearly illustrated in Figures 1 and 2. The slide 92 is equipped with a roller 94 at its lower end which engages the periphery of the cam 48 so that the rod 87 will be twice depressed and released for upward movement during each rotation of the cam shaft 43. The parts are so adjusted that when the roller 94 is against, or approximately against either dwell portion 50 of the cam, the depressor finger carrying arm 72, and the finger 71 will partake of a four-motion movement in the manner, and for a purpose which will be described in greater detail hereinafter. The inward and downward movement of the arm and finger is yieldably transmitted through the compression spring 88, and said spring permits a greater amount of downward movement of the actuator rod 87 than is necessary to bring about the desired downward or depressed movement of the depressor finger.

Referring now to Figures 1, 4 and 5 of the drawings, it will be apparent that the other angle member 53 is secured as at 95 to and supports an uprightly disposed supporter member 96, and a second housing member 97 is vertically-slidably mounted as at 98 on said supporter member. At its lower end the housing member 97 is equipped with a cam engaging projection 99 which is secured thereto as at 100, and it will be apparent by reference to Figures 5 and 6 of the drawings that a finger piece 101 is secured to and extends from the member 99 so as to permit manual lifting and lowering of the vertically-slidable housing member. It is intended that during the can end feeding operation the housing member 97 is lifted during the outfeeding of each can end, and for this purpose a cam bar 102 is secured as at 103 on a bracket 104 which is attached at 105 to one of the laterally reciprocable slides 40, and said cam bar is equipped with a cam nose 106 which is engageable under the extension 99 for automatically effecting the lifting of the housing member 97 as said slide is moved inwardly, and the lowering of said housing member as said slide is moved outwardly.

A support member 107 in the form of a short pin projects inwardly from the inner face of the housing member 97 adjacent the lower end thereof, and this pin serves to support the weight of the major part of a stack of can ends opposite the depressor finger 71 so that the upward tilting of can ends at the bottom of the stack effected by operation of the depressor finger 71 is not re-

sisted by the weight of the stack. The pin 107 performs a second function of isolating the upper part of the stack from agitation of the can ends at the bottom of the stack by action of the depressor finger 71 and lifting slide members later to be described so that said agitation will not be effective to displace can ends from the top of the stack.

It will be apparent by reference to Figures 3 and 5 of the drawings that two longitudinal bars 108 are secured as at 109 to the bed 8, one at each side of the feed bar groove 9. Clamp pieces 110 are secured as at 111 to the inner faces of said bars and have inwardly angled upper edge portions 112 which overlie the feed bar 10 in a manner for preventing upward displacement thereof at the position of the stack. Two rows of permanent magnets 113 are carried by the bars 108 and these magnets serve to firmly hold the lowermost can end in the stack against upward displacement during the tilting and lifting of can ends thereabove, and said magnets also hold the can ends against the feedway and facilitate the individual feeding of the can ends away from the bottom of the stack.

At the position of the slides 40 the bars 108 are provided with cam surfaces 114 in the manner clearly shown in Figure 3. Slide members 115 are adjustably secured as at 116 on the respective slides 40, and each said slide member is provided with a groove 117 at its upper surface. It will be apparent by reference to Figures 3 and 5 that a lifter blade carrier 118 is pivotally mounted as at 119 in each slide member groove 117, and each said carrier is equipped with a cam surface 120 for cooperating with the opposing cam surface 114 of the respective bar 108. A lifter blade 121 is secured as at 122 to project inwardly from each carrier 118, and the upper inner edge portion of each blade is bevelled as at 123. It will also be apparent by reference to Figure 5 that the ends of the bevelled portions 123 extending in the direction in which the can ends are fed are inwardly projected as at 124. The outer end portion of each carrier 118 is urged upwardly by a compression spring 125 interposed between said end and the underlying portion of the respective slide member 115, and thus the springs constantly tend to depress the blades 121. As the slides 40 are reciprocated laterally by oscillation of the bell crank levers 36 the blades 121 will be moved inwardly and outwardly. As each carrier 118 moves inwardly its cam surface 120 will engage and ride upwardly on the cooperating bar cam surface 114 so that the inner edge extremities of the blades will move inwardly and upwardly as they engage between can ends at the bottom of the stack. During the inward movement of the slides, the slide portions 126 form stops engageable with the bars 108 for limiting inward movement of said slides. As the slides move outwardly, the cam surfaces will disengage and the inner ends of the carriers and the blades thereon will be depressed. It will be obvious by reference to Figure 2 that the spring 33 tends constantly to hold the stop shoulders 126 against the bars 108.

As previously stated, the apparatus described herein is designed for the stacking and feeding of can ends which are elliptical or oval in shape. These ends are generally designated 127 and each includes a central raised portion 128 and an outwardly extending flat flange 129 terminating in a raw metal peripheral edge. As previously stated, hat-shaped can ends of shapes other than oval or elliptical may be stacked and fed by the

apparatus covered herein, and it is to be understood that the opposing faces of the stack supporting housings 58 and 97 will be shaped according to the variation in shapes of the can ends stacked therein.

In operation, rotation of the main drive shaft 20 imparts reciprocation to the feed bar 10 through the crank and link connections 18, 17, 14, 13, and the cam shafts 22 and 43 are rotated once for each two rotations of the main shaft through the gear couple 21 and the sprocket and chain connections 44 as hereinbefore described.

A stack of the hat-shaped can ends 127 is mounted between the housing members 58 and 97 with the major portion of the weight of the stack at the side opposite the depressor finger 71 being supported by the pin 107 in the manner, and for the reasons hereinbefore described. The lowermost can end in the stack always will be firmly held by the underlying permanent magnets 113, and as the depressor finger partakes of its four-motion movement by reason of the oscillation of the arm 79, it will first move from the position illustrated in Figure 10 inwardly between the flanges of the second and third ends in the stack, or between the flanges of two other can ends in the path of its movement but always at least as high as the second can end, as illustrated in Figure 11, then move downwardly as shown in Figure 3 so as to displace the engaged can end at the left as viewed in this figure and effect a lifting or tilting of the right hand side of said can end upwardly as shown in Figure 12, thereby to provide a space between the lowermost can end and the upwardly tilted can end immediately above the same. The movements of the depressor finger from the Figure 10 position through the positions of Figures 11 and 12 are brought about by yieldable depression of the arm 79 through the spring 88. As the roller 94 passes over the respective cam crest 49 and starts down the merging downward slope toward the oncoming concentric portion 50, the rod 87 will be moved upwardly and the arm 79 will be moved upwardly by the abutment 85 to first swing the depressor finger outwardly to the position illustrated in Figure 13 and then upwardly to the position illustrated in Figure 10, thereby completing the four-motion cycle of movement of the depressor finger. It will be apparent that each time the arm 97 starts an upward or downward movement it first effects a swinging of the arm 72 about the slide pivot 76 either from the position illustrated in Figure 10 to that illustrated in Figure 11, or from the position illustrated in Figure 12 to that illustrated in Figure 13. The continuation of the upward or downward movement of the free end of the arm 79 will cause the arm 72 to slide bodily upwardly or downwardly as from the position illustrated in Figure 13 to the position illustrated in Figure 10, or from the position illustrated in Figure 11 to the position illustrated in Figure 12. The provision of the spring 88 not only provides for a yielding action effective to assure against damaging of can ends during the depression of the can ends at one side as illustrated in Figure 12, but it also allows the actuator rod 87 to partake of a considerable amount of idle movement, that is movement not necessary to the effecting of the desired depression of the can ends.

The parts preferably are so timed that when a given crest 49 of the depressor finger actuator cam 48 is centered over the roller 94, the depressor finger 71 will have been dwelling a moment in the can end depressing position illustrated in Fig-

ure 12, and at this time the slide blades 121 will have started their inward travel so that they will be about to engage between the lowermost two can ends. As previously explained, this inward movement of the blades and the slides which carry the same is brought about by downward pulling of the actuator rod 32 by the anchored spring 33 under control of the engagement of the roller 29 with the respective crest 26 of the cam, or rather the effective portion receding beyond the crest toward the end of the effective portion at 28 where said effective portion merges into the concentric dwell portion of said cam.

While the can ends are being depressed in the manner illustrated in Figure 12, or in other words at the time when the roller 94 has passed only slightly beyond the respective crest 49, the blades 121 will have proceeded inwardly to the position illustrated in Figures 3 and 5. It will be noted that in this position the inwardly directed nose portions of the blades will have engaged in the space provided between the first and second can ends by the upward tilting thereof, and in their inward and upward movement they will engage under the flange of the second end in the stack and fully lift in above the underlying first can end in the manner illustrated in dotted lines in Figure 3 and in Figure 13. At this time the depressor finger 71 is retracted as shown in Figure 13 but has not been returned to the elevated position illustrated in Figure 10. When the blades have reached the inner limit of their travel the slide shoulders 126 will engage as stops with the bed bars 108, and at this time the roller 29 on the arm 30 will be engaging one of the concentric dwell portions of the cam 25 or slightly out of contact therewith. During this dwelling of the can end lifting and supporting blades 121, the endmost feed finger on the feeder bar 10 will move into position behind the lowermost separated can end, and upon retraction of the feed bar will feed said can end over the feedways toward the work station at which the sealing compound is applied to the can end or other work is performed thereon. After said can end is fed away, the slides are retracted to their outer positions by the riding of the roller 29 up the oncoming crest 26, effective engagement commencing at 27 as previously described, thus completing the finger feeding cycle.

It is to be understood that the parts may be so adjusted and timed that the endmost feed finger 11 on the feed bar 10 may move all the way past the stack so as to engage behind the flange 129 of the separated lowermost can end, or the parts may be adjusted so that said finger engages with the raised central portion 128 of said lowermost can end and against the near wall thereof for effecting the desired feeding of the end.

At the time said endmost feed finger is in fully projected position, ready to take away the lowermost, separated can end, the depressor finger 71 is elevated in the position illustrated in Figure 10 and the slide roller 94 will be engaged approximately centrally of one of the concentric dwell portions 50 of the cam 48.

The invention is herein disclosed as adapted for feeding can ends with the central raised portions 128 thereof extending upwardly, as when said can ends are to have sealing compound applied thereon and then be edge curled. It is to be understood however that the apparatus will function as efficiently when the can ends are disposed with their central raised portions extending downwardly, as they would be should the apparatus be employed to feed can ends into posi-

tion for being applied as top end closures to be double seam secured on container bodies. In such an adaptation of the invention, it would only be necessary to slightly adjust the position of the depressor finger 71 and to alter the position of the feeder fingers slightly to adapt them for suitable engagement with the inverted can ends.

While one form of the invention has been shown for purposes of illustration, it is to be clearly understood that various changes in the details of construction and arrangement of parts may be made without departing from the spirit and scope of the invention as defined in the appended claims.

I claim:

1. In apparatus of the character described for stacking and feeding can ends having upstanding central portions which tend partially to nest and outwardly extended generally flat flange portions, in combination, stack supporting means, a reciprocable depressor, means for engaging said depressor with the upper surface of the flange of a can end above the lowermost can end in the stack for depressing said engaged can end flange at one side to cause the can end immediately above the can end which is lowermost in the stack to fulcrum on said lowermost can end and be lifted at the opposite side and provide a space between said lowermost can end and said can end immediately thereover at the side of said lift, at least one separator blade movable into said space for effecting a full separation of said lowermost and immediately overlying can ends, and means for feeding away said lowermost separated can end.

2. In apparatus of the character described for stacking and feeding can ends having upstanding central portions which tend partially to nest and outwardly extended generally flat flange portions, in combination, stack supporting means, a reciprocable depressor, means for engaging said depressor with the upper surface of the flange of a can end above the lowermost can end in the stack for depressing said engaged can end flange at one side to cause the can end immediately above the can end which is lowermost in the stack to fulcrum on said lowermost can end and be lifted at the opposite side and provide a space between said lowermost can end and said can end immediately thereover at the side of said lift, at least one separator blade movable into said space for effecting a full separation of said lowermost and immediately overlying can ends, magnet means disposed beneath the can end stack for holding said lowermost can end in place during said depressing and separation of can ends and the fulcruming of the overlying can end over the lowermost magnet held can end, and means for feeding away said lowermost separated can end.

3. In apparatus of the character described for stacking and feeding can ends having upstanding central portions which tend partially to nest and outwardly extended generally flat flange portions, in combination, stack supporting means, means engageable with the upper surface of the flange of a can end above the lowermost can end in the stack for depressing said engaged can end flange at one side to cause the can end immediately above the can end which is lowermost in the stack to fulcrum on said lowermost can end and be lifted at the opposite side and provide a space between said lowermost can end and said can end immediately thereover at the side of said lift, at least one separator

blade movable into said space for effecting a full separation of said lowermost and immediately overlying can ends, said depressing means comprising an upwardly and downwardly movable member disposed adjacent the bottom of the stack and means for engaging said member with the top surface of the flange of a can end not far removed from the bottom of the stack, and means for feeding away said lowermost separated can end.

4. In apparatus of the character described for stacking and feeding can ends having upstanding central portions which tend partially to nest and outwardly extended generally flat flange portions, in combination, stack supporting means, an upwardly and downwardly reciprocable depressor, means for engaging said depressor with the upper surface of the flange of a can end above the lowermost can end in the stack for depressing said engaged can end flange at one side to cause the can end immediately above the can end which is lowermost in the stack to fulcrum on said lowermost can end and be lifted at the opposite side and provide a space between said lowermost can end in the stack and the can end thereover at the side of said lift, separator blade means movable into said space for effecting a full separation of said lowermost and immediately overlying can ends, a support pin projecting toward said depressor and effective to support the weight of the major part of the can end stack at said can end lifting side excepting only a limited number of the ends at the lower part of the stack thereby to relieve the depressing means of said supported weight and avoid transmitting to top can ends in the stack agitation incidental to said lifting at the bottom of the stack, and means for feeding away said lowermost separated can end.

5. In apparatus of the character described, in combination, can end stack supporting means, reciprocable blade means for lifting can ends of the stack to space the lowermost can end in the stack from the one thereover, feeding means for feeding away from beneath the can end spaced thereover, and in the general plane in which it lies, said lowermost can end, said stack supporting means including a vertically movable housing member serving at least in part as a confining guide for the can ends as they are lifted, cam means movable with said blade means and engageable under a part of said housing member, and means for moving the cam means for lifting said housing member each time the feeding of a lowermost can end occurs to permit said can end to pass under said housing member without contacting the same.

6. In apparatus of the character described, in combination, can end stack supporting means, reciprocable blade means for lifting can ends of the stack to space the lowermost can end in the stack from the one thereover, feeding means for feeding away from beneath the can end spaced thereover, and in the general plane in which it lies, said lowermost can end, said stack supporting means including a vertically movable housing member serving at least in part as a confining guide for the can ends as they are lifted, and means movable with said blade means for lifting said housing member each time the feeding of a lowermost can end occurs to permit said can end to pass under said housing member without contacting the same, a support pin projecting from and movable with said movable housing member in position for supporting the

weight of a major part of the can end stack excepting only a limited number of the ends at the lower part of the stack thereby to relieve the separator blade means of said pin supported weight.

7. In apparatus of the character described for stacking and feeding can ends having upstanding central portions which tend partially to nest and outwardly extended generally flat flange portions, in combination, stack supporting means, an upwardly and downwardly reciprocable depressor, means for engaging said depressor with the upper surface of the flange of a can end above the lowermost can end in the stack for depressing said engaged can end flange at one side to cause the can end immediately above the can which is lowermost in the stack to fulcrum on said lowermost can end and be lifted at the opposite side and provide a space between said lowermost can end and said can end immediately thereover at the side of said lift, and means for feeding away said lowermost can end in a direction away from said depressing means.

8. In apparatus of the character described for stacking and feeding can ends having upstanding central portions which tend partially to nest and outwardly extended generally flat flange portions, in combination, stack supporting means, means engageable with the upper surface of the flange of a can end above the lowermost can end in the stack for depressing said engaged can end flange at one side to cause the can end immediately above the can end which is lowermost in the stack to fulcrum on said lowermost can end and be lifted at the opposite side and provide a space between said lowermost can end and said can end immediately thereover at the side of said lift, and means for feeding away said lowermost can end in a direction away from said depressing means, said depressing means including a swingably mounted depressor finger and means for swinging it between can end flanges above the flange of the end overlying the lowermost end in the stack then moving it bodily downwardly against the top surface of an underlying can end flange for depressing the engaged flange, then outwardly from between flanges.

9. In apparatus of the character described for stacking and feeding can ends having upstanding central portions which tend partially to nest and outwardly extended generally flat flange portions, in combination, stack supporting means, means engageable with the upper surface of a can end flange for depressing one or more can ends at one side to cause the can end immediately above the can end which is lowermost in the stack to fulcrum on said lowermost can end and be lifted at the opposite side and provide a space between said lowermost can end and said can end immediately thereover at the side of said lift, and means for feeding away said lowermost can end in a direction away from said depressing means, said depressing means including a generally horizontally disposed depressor finger, an upright arm disposed at one side of the stack supporting means and carrying said finger and having a generally horizontally disposed arm extension, means limiting inward and outward swinging movement of said upright arm, support means, a pivot for said arm upwardly and downwardly slidably on said support means, and means for moving the horizontally disposed arm extension upwardly and downwardly about the pivot to cause the pivot to slide upwardly and downwardly, the arm to swing inwardly and outward-

ly about the pivot and the finger to partake of four-motion movement and first move in between can end flanges, then downwardly for depressing one or more flanges, then outwardly from between flanges and then upwardly.

10. In apparatus of the character described for stacking and feeding can ends having upstanding central portions which tend partially to nest and outwardly extended generally flat flange portions, in combination, stack supporting means, means engageable with the upper surface of a can end flange for depressing one or more can ends at one side to cause the can end immediately above the can end which is lowermost in the stack to fulcrum on said lowermost can end and be lifted at the opposite side and provide a space between said lowermost can end and said can end immediately thereover at the side of said lift, and means for feeding away said lowermost can end in a direction away from said depressing means, said depressing means including a generally horizontally disposed depressor finger, an upright arm disposed at one side of the stack supporting means and carrying said finger and having a generally horizontally disposed arm extension, means limiting inward and outward swinging movement of said upright arm, support means, a pivot for said arm upwardly and downwardly slideable on said support means, and means for moving the horizontally disposed arm extension upwardly and downwardly about the pivot to cause the pivot to slide upwardly and downwardly, the arm to swing inwardly and outwardly about the pivot and the finger to partake of four-motion movement and first move in between can end flanges, then downwardly for depressing one or more flanges, then outwardly from between flanges and then upwardly, said last named means including a yieldable element effective to impart the movement of the finger in the flange depressing direction.

11. In apparatus of the character described, can end flange depressing can end tilting means comprising a depressor finger, an elongated finger carrying arm from which the finger projects in angular relation for being projected between can end flanges and having an extension projecting in angular relation therefrom, a pivot for said arm and extension, support means, means mounting said pivot on said support means for sliding movement in the direction of the length of said arm, means for permitting a limited amount of swinging movement of the arm for projecting the finger between can end flanges and for retracting it therefrom, and means reciprocable in the general direction of the length of said arm and connected with the extension so as to be effective for swinging it and the arm about said pivot and for moving said extension and arm bodily with the pivot in the direction of the length of the arm thereby to impart four-motion movement to said finger.

12. In apparatus of the character described for stacking and feeding can ends having up-

standing central portions which tend partially to nest and outwardly extended generally flat flange portions, in combination, stack supporting means, a reciprocable depressor, means for engaging said depressor with the upper surface of the flange of a can end above the lowermost can end in the stack for depressing said engaged can end flange at one side to cause the can end immediately above the can end which is lowermost in the stack to fulcrum on said lowermost can end and be lifted at the opposite side and provide a space between said lowermost can end and said can end immediately thereover at the side of said lift, at least one separator blade movable into said space for effecting a full separation of said lowermost and immediately overlying can ends, and means for feeding away said lowermost separated can end, said separating means including a pair of slides movable toward and from each other and including can end separating and lifting blade portions having leading nose portions extending toward each other and laterally in the general direction in which the can ends are fed and toward the lifted ends of the can ends and engageable in said space between the lowermost can end and the lifted can end and merging into main body portions of the blades so as to be effective to progressively effect a lifting of the can end overlying the lowermost can end to a horizontal position wholly separated from said lowermost can end.

13. Apparatus as defined in claim 11 in which the finger carrying arm is equipped with a cross bore, and said arm is mounted between two parallel wall portions of said support means, and in which the arm pivot comprises a pair of pins mounted in said bore and held in sliding frictional contact with said wall portions by a compression spring interposed therebetween within said bore.

FERDINAND KASTEL.
